UNITED STATES PATENT OFFICE.

SILAS B. RITTENHOUSE AND JAMES FREEMAN RITTENHOUSE, OF LIBERTY MILLS, INDIANA;
CLARISSA L. RITTENHOUSE, EXECUTRIX OF SAID SILAS B. RITTENHOUSE, DECEASED,
ASSIGNOR TO SAID JAMES FREEMAN RITTENHOUSE.

HAND-SEEDER.

No. 927,429.

Specification of Letters Patent.

Patented July 6, 1909.

Application filed July 16, 1908. Serial No. 443,771.

To all whom it may concern:

Be it known that we, SILAS B. RITTENHOUSE and JAMES FREEMAN RITTENHOUSE, citizens of the United States of America, residing at Liberty Mills, in the county of Wabash and State of Indiana, have invented certain new and useful Improvements in Hand-Seeders, of which the following is a specification, reference being had therein to the accompanying drawings, in which—

Figure 1 is a top view of the seeder; Fig. 2 is a bottom view of the same; Fig. 3, a side elevational view of the same in an inverted position; Fig. 4, a view of the hopper closing devices; Figs. 5, 6, 7, 8 and 9 views of details described hereinafter.

Our invention relates to improvements in broad-cast hand-seeders in which a distributor wheel is rotated by means of gears operative from a crank; and the objects of our invention are to provide a hand-seeder with a distributor wheel which is formed of a single sheet of metal and mounted on its shaft without soldering; to provide a simple mechanism by which the distributor wheel may be rotated; to provide a slide which shall be capable of adjustment in its movement in order to regulate the size of the delivery opening of the hopper for different seeds, all as hereinafter described and pointed out in the claims.

Referring to the drawings, we provide a board 1 which forms the bottom of the seed holding bag 2 and also a support for the operating mechanism. Board 1 is provided with a circular opening 3 for the seed to pass through, half of which opening is closed by a plate 4 secured by screws 5 to the under side of board 1. Plate 4 is provided with an opening in the form of a half cylinder, the curved portion of which practically coincides with the curved edge of opening 3. Under this plate is placed a slide 6, having a curved segment removed from its front portion thereby producing a curved concave edge 6' to operate in connection with straight edge 4' in plate 4 to regulate the passage of the seeds. Slide 6 is retained on board 1 by screws 5 and 5' and is movable under those screws by a rod or lever 7 which is pivoted to board 1 at 8 and passes through lug 9 on slide 6 and also passes through a suitable guide 10 on board 1. We regulate the movement of lever 7 by a bar 11, one end

of which passes under the lever and is provided with an abutment 12. A thumb nut 13 which passes through a slot 14 in bar 11 serves to fix bar 11 in the desired position. A suitable division scale 15 on board 1 enables the operator to adjust bar 11 for any desired seed. By this regulation of the movement of lever 7 the movement of slide 6 is, of course, regulated to provide the proper opening for the discharge of the seed which it is desired to feed into the distributor wheel.

The shaft 17 of the distributor wheel 16 passes through an opening in lug 18 on plate 4, the upper end being provided with a stirrer 19 and the lower end passing through a support 20, the extremity of support 20 at this point being doubled or turned on itself to furnish a suitable bearing for shaft 17. Shaft 17 carries a pinion 21 which meshes with gear wheel 22, the latter being mounted on a support 23. Support 23 is fixed to support 20 as by rivet 24 and is provided with legs 25 and 26 in which is mounted shaft 27, which shaft carries gear wheel 28. Gear wheel 28 meshes with pinion 29 mounted on gear wheel 22. Shaft 27 terminates in crank 30 by which the several gear wheels and pinions and distributor wheel 16 are rotated. The end of one leg 25 of support 23 is doubled on itself to furnish a suitable bearing for shaft 27. This leg is also fixed to a support 31 which is mounted on shield 32.

Distributor wheel 16 comprises a single sheet of metal, such as tin, having a tapering wing or prong formed on each end, with an upwardly projecting flange on each side intermediate the two wings or prongs, as shown in Fig. 3. An upright rib 16', extending from end to end of the plate, is pressed into the same by doubling the metal over on its longitudinal axis. An opening 16² is provided in the center through the rib, through which opening shaft 17 is adapted to project. Wheel 16 is held fast to shaft 17 by a ferrule 16³ and rivet 16⁴ which passes through the ferrule, rib 16' and shaft 17. Slot 16⁵ and the lower portion of slot 16⁶ permit the ferrule to engage both sides of rib 16' as those sides surround shaft 17.

The curved strip 33 mounted on board 1 and attached to shield 32 is adapted to be placed against the person of the operator as he grasps handle 34 with one hand. The

other hand is thus free to manipulate crank 30 to rotate the distributor wheel. The free end of lever 7 is curved up over the edge of board 1 and also inclined toward shield 32 5 so as to be easily accessible to the hand grasping handle 34. The operator may thus manipulate slide 6 with his thumb without releasing his hand from handle 34.

To regulate the size of the discharge opening in board 1 for any particular seed, it is 10 only necessary to adjust bar 11 to the desired point on scale 15, thumb nut 13 is tightened, and as abutment 14 lies against rod 7, the movement of that rod and slide 6 15 away from the discharge opening in board 1 is thereby limited. When slide 6 has been moved to close discharge opening 3 and it is desired to again distribute the seed, rod 7 is moved until it strikes abutment 14, and 20 since that abutment is temporarily fixed, a discharge opening of constant cross sectional area is assured for any given seed.

We provide a notch or recess 20' in support 20 near shaft 17 to enable the assembler 25 or operator to mesh pinion 21 with gear wheel 22. Notch or recess 20' weakens support 20 at this point sufficiently to permit the bending of that support toward or away from gear wheel 22 should pinion 21 at any 30 time not properly mesh with gear wheel 22.

By forming the distributor wheel of a single piece of metal no sharp edges occur at any point which will mutilate or damage the seed, and as no soldered parts are used there 35 is nothing about the wheel to be separated or loosened on its shaft by blows from the seed as is often the case with distributor wheels having soldered parts. The supporting frame for the wheel driving gear is very 40 simple and rigid, the shaft bearings are efficient and simple of construction and the rotation of the distributor wheel is effected with great ease and convenience.

What we claim is:

45 1. A hand seeder comprising a bottom board having an opening therein, a plate covering part of said opening, an adjustable slide adapted to close the remaining portion of said opening, a distributor wheel formed 50 from a single sheet of metal and having a continuous rib pressed therein from end to end, a shaft passing through said plate and through the wheel, said wheel being retained on the shaft by a slotted ferrule, a crank, and 55 gears and pinions connecting the crank and shaft whereby the distributor wheel is rotated.

60 2. A hand seeder comprising a bottom board having an opening therein, a plate covering part of the opening, an adjustable slide adapted to close more or less the remaining

portion of the opening, a distributor wheel formed from a single sheet of metal and having a continuous longitudinal rib pressed therein and extending from end to end thereof, a perpendicular opening through the said rib adapted to receive a shaft, the shaft being retained within the opening by a ferrule which is slotted to enable the sides of the ferrule to engage the expanded sides of the rib 70 about said opening, a crank, and gears and pinions between the crank and shaft whereby the distributor wheel is rotated.

65 3. In a hand seeder the combination with a bottom board having an opening therein, 75 of a shaft projecting into said opening and having a stirrer operative within the opening, a distributor wheel formed of a single sheet of metal and having a continuous rib pressed therein and extending from end to end thereof, a perpendicular opening in the rib to receive the shaft, and a ferrule mounted on the shaft and engaging the sides of the rib adjacent to said opening.

80 4. In a hand seeder the combination with a bottom board having an opening therein, 85 of a shaft mounted over and projecting into the opening, a distributor wheel mounted on the shaft, a pinion on the shaft, the lower end of the shaft having a bearing in a support 90 mounted on the bottom board, the bearing being formed by doubling or folding over the free extremity of the support, a recess in the support adjacent to the bearing, and means 95 for rotating the pinion and shaft and means on the support by which the shaft and pinion may be adjusted laterally for the uses and purposes described.

5. In a hand seeder the combination of a bottom board having an opening therein, a 100 plate covering a portion of said opening, a slide adapted to coöperate with said plate to vary the cross sectional area of the remaining portion of said opening, a shaft mounted in said plate and having mounted thereon a distributor wheel and carrying at its lower end a pinion, a support mounted on the bottom board provided at its free end with a bearing for said lower end of the shaft, a recess in the support adjacent to the bearing whereby the 110 bearing is adapted to be transversely adjustable, a crank, and gearing between the crank and pinion whereby the distributor wheel is rotated.

115 In witness whereof we hereunto subscribe our names in the presence of two witnesses.
